UNITED STATES PATENT OFFICE

MARIE-LOUIS RIVIERE, OF PARIS, FRANCE

SAFETY RAZOR

Original application filed March 2, 1928, Serial No. 258,568, and in France September 13, 1927. Divided and this application filed December 15, 1928. Serial No. 326,338.

This invention relates to improvements in folding safety razors comprising a support or blade holder to which is pivoted a blade of suitable rigidity.

5 The invention relates more particularly to a construction of a folding safety razor with a protecting plate removably arranged above the edge of the blade so as to prevent any danger of cutting the operator of same.

10 In the accompanying drawing which shows by way of example constructions of a razor embodying the improvements according to the invention—

15 Figures 1 and 2 are a rear elevation and a side view showing said razor in folded and operative position respectively.

Figures 3 and 4 are a front elevation and a profile view respectively of an embodiment of the shield.

20 Figures 5 and 6 show on an enlarged scale, in two different positions, a section of the joint of the shield.

Figure 7 shows a modified construction of the said shield.

25 Figure 8 is a modified construction of Figures 5 and 6.

As shown in Figures 1 and 2, the shield 28 is hinged with its foot 32 to lugs 33, each of which (Figures 3 and 4) is secured to a rod 34 terminating in a head 35 on which acts a spring 36 which always tends to bring the shield 28 to the closed position shown in full lines in Figure 4 in which it covers the edge of the blade 1.

35 In the modified construction in Figure 8, the lugs 33 are rigidly secured to the head 8 of the fork, and a spring 37 presses against the foot 32 of the shield 28 by means of a cap 38.

40 In the modified construction of Figure 7, the shield 28 has a projection or rib 39 which, in the folded position of the razor, rests on the teeth 40 of the safety razor guards, so that when the blade holder 3 is turned between the branches 4 of the elastic fork 8 in order to bring it into the position of use, the shield 28 is automatically raised by the teeth 40 without allowing any contact between the edge of the blade 1 and the said shield 28.

50. What I claim is:—

1. A safety razor of the folding type comprising a thick razor blade having a cutting edge, a blade holder supporting said razor blade, an elastic fork pivotally supporting said blade holder, a shield pivotally mounted with respect to said elastic fork adjacent said cutting edge of said razor blade when the razor is folded and moved into open position by said blade holder when the razor is opened, and resilient means adapted to resiliently hold said shield in closed and open positions.

2. A safety razor of the folding type comprising a thick razor blade having a cutting edge, an elastic fork pivotally supporting said razor blade, rods having heads slidably mounted in said elastic fork, a shield hinged to the ends of said rods adjacent said cutting edge of said razor blade when the razor is folded and springs encircling said rods abutting said heads and said elastic fork. 65 76

3. A safety razor of the folding type comprising a thick razor blade having a cutting edge, a blade holder supporting said razor blade, an elastic fork pivotally supporting said blade holder, a shield pivotally mounted with respect to said elastic fork adjacent said cutting edge of said razor blade when the razor is folded, a rib integral with said shield abutting said blade holder when said razor is folded and moved into open position by said blade holder upon opening of said razor, and resilient means adapted to resiliently hold said shield in closed and open positions.

In testimony whereof I have hereunto set my hand.

This 27th day of November, 1928.

MARIE-LOUIS RIVIERE.
